UNITED STATES PATENT OFFICE.

PAUL E. HERRMANN, OF NEW YORK, N. Y.

APPARATUS FOR HAIR WAVING.

Application filed February 27, 1923. Serial No. 621,571.

To all whom it may concern:

Be it known that I, PAUL E. HERRMANN, a citizen of the United States, residing at New York, in the county of New York and State of New York, have invented certain new and useful Improvements in Apparatus for Hair Waving, of which the following is a specification.

This invention relates to an apparatus for curling or waving hair and more particularly to an apparatus of the type described in my U. S. Letters Patent #1,199,550 in which the liquid or lotion required for the treatment is applied to an absorbent lining of shell of the apparatus.

The main object of this invention is to materially simplify the construction of the steaming device used in connection with said apparatus and reduce the number of parts composing the same, so as, thereby, not only to lower the cost of manufacture but also reduce the weight and render the handling of the device comfortable.

Another object is to provide the apparatus with means for replenishing the liquid as the latter is being evaporated.

A still other object is to provide a shield or hair protector, whereby escaping steam will be prevented from scalding the head of the person treated.

And a further object is to provide a construction in which the heater and steaming device are bodily combined to a single device.

With these and other objects in view, my invention consists in the novel construction, combination and arrangement of parts, as will be hereinafter more fully described and defined in the appended claims.

In the accompanying drawing, in which similar reference characters denote corresponding parts, Fig. 1 is a longitudinal section of the complete apparatus; Fig. 2 is a cross section on line 2-2 of Fig. 1; Fig. 3 is a cross section on line 3-3 of Fig. 1; Fig. 4 is a cross section on line 4-4 of Fig. 1; Fig. 5 is a longitudinal section of the rear end of the steaming device and of a modified stopper; Fig. 6 is a cross section on line 6-6 of Fig. 5; Fig. 7 is an end view of my improved hair protector used in connection with this apparatus; Fig. 7a is a cross section on line 7a-7a of Fig. 7; Fig. 8 is a longitudinal section of the front end of the steaming device with the modi-

fied shield applied thereto; Fig. 9 is a longitudinal section of a modified steaming device; Fig. 10 a cross section on line 10-10 of Fig. 9; Fig. 11 a perspective view of a detail of the steaming device; Fig. 12 is a sectional view of a steaming device with the heater directly formed thereon, Fig. 13 is a view similar to Fig. 7 showing a shield with modified locking means; Fig. 14 is a cross section of the steaming device showing means for tightening the forward end of the lining and Fig. 15 is a longitudinal section of the forward end of the steaming device, showing a modified construction of the tightening means.

The heating apparatus according to the construction shown in the patent above referred to, comprises a cylindrical casing *a* provided with a hollow handle *b* of heat insulating material, a tubular shell *c* centrally and longitudinally disposed in said casing and constituting with the latter an annular heating chamber containing an electric heating coil *d*, the terminals of which are connected with the wires *e* leading through said handle *b*.

The steaming device forming part of this invention, comprises a tubular member 10 of metal or other heat conducting material, which is formed with an inner lining or shell 11 of suitable liquid absorbing material, such as asbestos or the like. This lining extends substantially throughout the length of the metal tube. 12 denotes a plate spring bent upon itself to form legs, and the latter are angularly bent substantially as shown. This spring is adapted to be placed in the tube 10, so that one of its legs extends between the asbestos shell or lining 11 and the other over the outer face of the tube. The bend 12' of the inner leg is adapted to spread the lining, so as to form a cavity 13 between the latter and the inner face of the tube 10, for the purpose to be hereinafter specified. The bends 12' in the outer leg serve as retaining members, and are adapted to frictionally engage the inner wall of the rigid shell *c* of the heater, so as to hold the steaming device in position within the heater. The spring 12 may be secured in position on the tube 10 by a band 14 of asbestos or the like suitably attached to the tube. The absorbent lining 11 may be secured in position in the tube 10 by a spring coil 15 or the like mounted 110

thereon and tending to hold it in frictional engagement with the wall of the tube 10.

The curler *f*, which may be of any suitable construction, such as the one shown in Fig. 8 and in my patent above referred to, is adapted to be inserted into the tube 10 to be surrounded by the lining 11 through one end thereof, after a lock or tress of hair is wound around it in the usual manner. The rear end of the tube 10 is adapted to be closed by a stopper *g*. The liquid which is poured into the tube or more correctly, into the shell 11, permeates into the cavity 13, which thus constitutes a reserve chamber. 15 When the current is turned on, the heat generated in the chamber of the heater liberates steam or vapor from the lotion absorbed by the lining or shell, which acts on the hair producing the desired permanent 20 curls or waves. The surplus liquid, which permeates into the cavity 13, will continue to feed the lining 11, as the liquid in the latter evaporates.

Instead of using the solid stopper *g*, a 25 hollow stopper or mouth piece 16 (Fig. 5) may be used. This mouth piece is formed with perforations 16' and may be made to snugly fit in the rear end of the tube 10 or shell 11. The outer end of the mouth piece 30 may be closed by a cap 17 threaded thereon. The mouth piece 16 is designed to serve as an auxiliary reserve tank, from which the liquid absorbed by the lining 11 will be replenished.

35 A still other modification of the steaming apparatus is shown in Figs. 9-11. Here between the metal tube 10 and the absorbent shell or sleeve 11, a feeder 18 is inserted. The latter consists of a rear hollow or cup shaped mouth piece 19 and two forwardly projecting hollow arms or forks 20 communicating with the interior thereof. The cup shaped mouth piece is adapted to fit more or less loosely in the rear of the metal 40 tube 10. Like the cup 16 shown in Fig. 5, the mouth piece 19 may be formed with perforations 19' opening into the annular space 10' between the tube 10 and said mouth piece and serving as passages for the 45 steam or vapor, as will be presently described. The rear end of this cup is open and adapted after filling the cup, to be closed by any suitable stopper such as 22. The arms or forks 20 projecting from the 50 inner wall of the mouth pieces 19 are adapted to extend to the front end of the tube and except for a short distance near the mouth piece are flattened or of substantially elliptical cross section with their inner faces con- 55 caved as at 20'. At their forward ends, there are a number of perforations, slits or recesses 20² in the inner face of each fork (Figs. 10, 11). Fitted in the front end of the tube 10 between the latter and the absorbent shell 11 is a channelled ring member

23, so disposed as to engage the free ends of the forks 20. This ring is retained in its end position by the inwardly curved portion 10² of the tube 10. The forks 20 are so spaced apart that, when passed between the tube 10 and lining 11, the latter will be spread or compressed at two diametrically opposed sides, the flattened portions of said forks causing the compressed parts of the shell to form comparatively wide flues or passages 24 through which the steam or vapor passing out from the arms 20 may flow back into the annular space 10' and thence re-enter the mouth piece 19 through the perforations 19' to mix with the lotion contained in said mouth piece. The curler *f* with the lock of hair wound around it is adapted to be inserted into the tube 10 through the front end thereof to be enveloped by the lining or shell 11. The liquid may be poured into the mouth piece 19, so as to cause it to pass through the openings 20' of the feeding arms 20 to the shell 11, which absorbs a part of it. After the insertion of the curler with the lock of hair wound around it, the steaming tube is heated, as in the first case, whereby the liquid absorbed by the lining of shell will vaporize and act on the hair producing the desired permanent wave. The steam or vapor will be allowed during the operation to continuously circulate through the flues 24, annular space 10', perforations 19', container 19 and feeding arms 20. The channelled ring in the front end of the tube serves to hold the ends of the forks 20, which are somewhat resilient, compressed against the lining, so as to frictionally engage the latter and hold it in position in the tube 10.

The apparatus may be still more simplified by utilizing the steaming tube 10 as part of the heater. To this end, a sleeve 25 of insulating material is fitted tightly over the rear end of the tube 10 and the electric coil 26 is wound around said sleeve. This coil is enclosed in a cup shaped casing 27 having central openings 27', 27² to snugly engage the tube 10. The rear end wall 27³ of the casing may be detachable to serve as a lid and may have suitably attached to it or formed integral with a handle 29 and with means (not shown) for attaching the wires to be connected to the coil 26.

The shield 30 used for protecting the head of the person treated against the escaping vapor, and adapted to be placed at the front end of the apparatus, is usually made in form of a circular disc composed of two pivotally connected segments 30', 30², cut out in the center as 30³ to engage the outer part of the lock of hair to be treated. It has been found, however, that such construction does not sufficiently protect against the escaping vapors. To obviate this drawback, I provide each section of the disc 30 with a marginal flange 31, so that when

the sections are in closed position they will together form a cap, which with its open end will fit around the forward end of the tube 10, closing the latter more or less 5 tightly as shown in Fig. 8. As shown in Figs. 7 and 7^a, one of the sections, as 30', has fixed to its inner face an auxiliary plate 32 to form between itself and the body portion a sheath for the engagement of the 10 other section in order that when closed, open crevices be avoided as much as possible.

For holding the sections 30', 30^a in closed position, they may be formed with suitable 15 snap members, such as a depression 33 and a projection 34, shown in Fig. 7 or one section may be provided with a spring catch 35 and the other with a toothed or serrated tongue 36 shown in Fig. 13. The spring catch may have a pin 37 projecting through 20 a perforation in the flange of the corresponding section, whereby the same may be disengaged from the tongue 36, when the sections are to be swung open.

25 The escape of vapor from the steaming device may be effectively prevented by using means for tightly closing the forward end of the steaming device. Thus in Fig. 14, the forward end of the lining 11 may be tightened around the curler to be passed 30 thereinto by a draw wire 38 or the like in a similar manner to a tobacco pouch. Or a band 39 of flexible material, such as asbestos, may be suitably fastened around the 35 forward end of the steaming tube 10 to extend forwardly and equipped with a draw wire 38 similar to the one shown in Fig. 14. By pulling the wire 38, either the lining or the band, as the case may be, will be tightly 40 closed around the curler.

What I claim and desire to secure by Letters Patent is:—

1. In a hair curling apparatus of the character described, a steaming device, comprising 45 a tube of heat conducting material, a shell or lining of liquid absorbing material in said tube and means therein for replenishing the liquid as it is being vaporized.

2. In a hair curling apparatus of the character described, a steaming device, comprising 50 a tube of heat conducting material, a shell or lining of liquid absorbing material in said tube and means between said tube and lining for replenishing the liquid as it is being vaporized.

3. In a hair curling apparatus of the character described, a steaming device, comprising 55 a tube of heat conducting material, a shell or lining of liquid absorbing material in said tube and a chamber or liquid container in said tube in communication with said lining for replenishing the liquid as it is being vaporized.

4. In a hair curling apparatus of the character described, a steaming device, comprising 60

ing a tube of heat conducting material, a shell or lining of liquid absorbing material in said tube and a liquid container communicating with said lining through the space between the latter and said tube for replenishing the liquid as it is being vaporized. 70

5. In a hair curling apparatus of the character described, a steaming device, comprising 75 a tube of heat conducting material, a shell or lining of liquid absorbing material in said tube, a liquid container in said tube, and means leading from said container and extending between said lining and said tube for feeding the liquid to said lining.

6. In a hair curling apparatus of the character described, a steaming device, comprising 80 a tube of heat conducting material, a shell or lining of liquid absorbing material, in said tube, a liquid container in said tube and hollow feeding members leading 85 from said container through the space between said lining and said tube and communicating with said lining for feeding the liquid thereto.

7. In a hair curling apparatus of the character described, a steaming device, comprising 90 a tube of heat conducting material, a shell or lining of liquid absorbing material in said tube, a liquid container in said tube and hollow members leading from said 95 container through the space between said lining and said tube and communicating with said lining, said members compressing said lining and forming passages between said lining and said tube for the steam 100 or vapor liberated from the liquid.

8. In a hair curling apparatus of the character described, a steaming device, comprising 105 a tube of heat conducting material, a shell or lining of liquid absorbing material in said tube, a liquid container in the rear end of said tube, hollow perforated arms leading from said container through the space between said lining and said tube to feed the liquid to said lining 110 and means for holding the free ends of said arms compressed against the lining to retain the latter in position within said tube.

9. An apparatus for permanent hair waving comprising a tube of heat conducting material, a lining or shell of liquid absorbing material in said tube, an electric heater including an electric coil mounted on the rear end of said tube and a casing enclosing said coil, means for replenishing 115 the liquid as it is being vaporized and a curler adapted to be passed into said tube to be encircled by said lining.

10. In an apparatus of the character described, a head shield composed of two pivoted segmental sections each centrally recessed to engage around a lock of hair and means for locking said sections in closed 125 position.

11. In an apparatus of the character de- 130

scribed, a head shield composed of two pivoted segmental sections each centrally recessed to engage around a lock of hair and snap members for closing said sections in closed position.

12. In an apparatus of the character described, a steaming device comprising a hollow member of heat conducting material, means of liquid absorbing material in said member and means for replenishing the liquid of the absorbent means as it is being vaporized.

13. In an apparatus of the character described, a steaming device comprising a hollow member of heat conducting material, means of liquid absorbing material in said

member and means for tightly closing the forward end of the steaming device.

14. In an apparatus of the character described, a steaming device comprising a hollow member of heat conducting material, means of liquid absorbing material in said member and flexible means at the forward end of said hollow member for tightly closing said end around the curler.
